UNITED STATES PATENT OFFICE.

WILLIAM A. KNAPP, OF WASHINGTON, DISTRICT OF COLUMBIA, ASSIGNOR, BY DIRECT AND MESNE ASSIGNMENTS, TO CHARLES SCHWARTZ, TRUSTEE, OF WASHINGTON, DISTRICT OF COLUMBIA.

PROCESS OF FITTING CAST-IRON ARTICLES TO OTHER BODIES IN CONNECTION WITH WHICH THEY WORK, AND PRODUCT OF SUCH PROCESS.

1,307,979.

Specification of Letters Patent. Patented June 24, 1919.

Application filed October 7, 1915, Serial No. 54,613. Renewed December 19, 1918. Serial No. 267,538.

To all whom it may concern:

Be it known that I, WILLIAM A. KNAPP, a citizen of the United States, residing at Washington, District of Columbia, have invented certain new and useful improvements in processes of fitting cast-iron articles to other bodies in connection with which they work, and products of such processes, of which the following is a specification.

10 My invention relates to a process of treating finished cast iron articles by which they are permanently heat-expanded, and consists of the process herein to be described and to the products of such process.

15 I have discovered that iron castings, when subjected to a red heat and then allowed to cool slowly, may become permanently expanded, that is to say, they do not, upon cooling, contract to the same sizes as they

20 had before being heated, but remain permanently enlarged to a perceptible degree. I believe that this is true of all kinds of iron castings, but the tendency to expand permanently is particularly pronounced in hollow castings, and more especially in those of cylindrical form, such as gas engine pistons. Furthermore, I have also discovered that castings so expanded may be again permanently expanded and the process repeated

25 30 until a substantial degree of enlargement is secured.

I have applied my invention practically to the expansion and refitting of worn or loose cast iron engine pistons, particularly to the pistons of gas engines, and more especially to those of engines used upon motor vehicles; and I shall in this application describe the process in connection with the expanding and refitting of such pistons, although the principle of the invention may be applied to advantage to the fitting of new pistons and cylinders, and to the expanding and fitting of other articles than pistons.

45 In the accompanying drawings—

Figure 1 is a longitudinal sectional view through the cylinder of an internal combustion engine, which has been used until the cylinder has become so worn that the piston no longer fits it accurately and tightly, the view being largely diagrammatic in its character, and the showing of the extent to which the cylinder is worn exaggerated;

Fig. 2 is a view illustrating one method of heating a piston to expand it; and

Fig. 3 is an elevation illustrative of the cooling step of the process.

In the expanding of an ordinary iron casting, such as the piston of an engine, I heat it to a temperature of between 1400 and 1600 degrees F. This heating may be in a furnace or a retort, or it may be by means of a blow torch. The latter method is illustrated in Fig. 2 where *a* indicates a hollow gas engine piston, *b* a jacket of non-combustible, heat-insulating material, such as asbestos, *c* a hot bed, as of glowing charcoal, upon which the incased piston is seated, and *d* a blow torch delivering flame into the interior of the piston for heating it. The illustration in Fig. 2 is typical, though practical and one that has been employed by me.

When the article being heated has been raised to the desired temperature the application of heat is discontinued and the casting allowed to cool slowly. This may be accomplished by removing the torch and covering the open end of the piston, as by means of a sheet of asbestos, such as indicated at *e* in Fig. 3. The jacket *b* and covering *e* not only insure a gradual and uniform cooling, but largely operate to prevent access of air to the article *a*, thus reducing the liability of the surfaces of the piston becoming oxidized and scaling.

On becoming cooled the casting will be found to have expanded slightly in all directions, and this expansion I have discovered remains permanent. If the expansion secured by a single heat treatment as described is insufficient for the purpose in view, the treatment is repeated, with the result that the casting will be again, and further, enlarged, the second expansion being also permanent, and this alternate heating and cooling may be carried on with safety a number of times so as to secure a considerable enlargement of the article.

One extremely useful and valuable application of my invention is to the refitting of pistons to engine cylinders where one or both have become worn. I refer to Fig. 1 of the drawings where *a* indicates the piston of a gas engine, and *f* the cylinder in which it works, these, particularly the cylinder, having become, through use, so worn that the

piston no longer fits the cylinder tightly. In practice the piston of a gas engine becomes somewhat reduced in diameter through wear, and the cylinder in which it works becomes 5 enlarged, particularly at those parts opposite which the piston travels, as indicated at *g* in Fig. 1, so that the cylinder becomes larger at the rear parts *g* than at the front portion *h*. When this occurs it is now the common practice to obtain a new "oversize" piston, and to rebore the cylinder to fit such piston. This practice is expensive and not always satisfactory, as the reboring is often attempted upon a machine not especially intended for that purpose, with the result that the engine cylinders are frequently seriously injured. Furthermore, the balance of the engine by the use of an oversize piston is disturbed, and this is believed by some to 10 injuriously affect the running of an engine thus equipped.

By the use of my invention I am enabled to overcome the objections to the use of an oversize piston replacing one that has become worn, to materially reduce the expense 15 incident to the installation of such a piston, and to insure a uniformly better result. To secure this I expand the worn piston, according to the method already herein described, until it is of a size to fit quite closely the front or outer end portion *h* of the cylinder—the part that is ordinarily least worn. I then insert this expanded piston into the open-end of the cylinder, and grind the latter, by means of the piston, using some 20 abrasive between them, taking off the high places and irregularities of the cylinder and bringing it to true cylindrical shape and to a slightly greater diameter than it originally had. If a single grinding be not sufficient the piston is a second time expanded and the grinding and shaping process just described repeated, and this is continued until the cylinder throughout its working portion is 25 brought to true cylindrical shape and of the desired diameter to fit the piston. Two or three alternate expanding and grinding operations have been usually found to be sufficient to restore a considerably worn cylinder to good working condition. Should the expansion of the piston at any time be found 30 too great to permit of its insertion into the end *h* of the cylinder, it may be reduced in diameter by turning. Not only is the process useful in refitting old pistons to old cylinders, but it will be found of advantage in obtaining a perfect fit between new cylinders and new pistons.

It is well understood that a better fit is obtained by grinding two parts together than where it is sought to secure the desired result by turning processes alone, and by my process the fitting, by the grinding together of cylinder and piston, is easily made practically possible.

The temperatures to which the articles being treated according to my process are heated, hereinbefore mentioned, that is, between 1400 and 1600 degrees F. are those that I have found the most practical under ordinary conditions, but they do not mark the limits of the temperatures between which my invention may be worked, because I have found that a temperature as low as about 1200° F. will cause a slight permanent expansion of an article subjected to that heat and treated according to the process herein described, and such relatively low temperature, or one between that and 1400° F. may be to advantage employed where a very slight expansion is desired. While I am not now able to fix the limits of temperature for heating the articles when practising my process, with accuracy, I believe that the term red heat describes with approximate accuracy the range of temperatures available for the heating step of the process.

It is evident that the specific gravity of an article expanded according to my process is less than that of ordinary cast iron, that is, cast iron that has not been expanded. I have expanded hollow pistons for internal combustion engines to a degree that perceptibly lowered their specific gravity, without, so far as I have been able to determine, impairing the strength and working qualities of the pistons, while, because of the lessened weight for size, such expansion has been of advantage.

What I claim is:—

1. The herein described process of fitting a cast iron article to another body in connection with which it works, which consists in permanently heat-expanding the article to a size approximating that it should have in order to properly work in coöperation with the other body, and then grinding the two together to accurately fit one another.

2. The process of enlarging and bringing to desired shape finished cast iron articles that have become worn in use, which consists in subjecting the articles to heat treatment by which they are permanently expanded to the desired size and then operating upon their surfaces to bring them to the finished shape and form desired.

3. The herein described process of fitting a cast iron piston to a cylinder in connection with which it is to work, which consists in permanently heat-expanding the piston to approximately the desired size, then grinding it and the cylinder together to cause them to accurately fit one another.

4. The herein described process of refitting a worn cast iron piston to a cylinder in which it works, which consists in first permanently expanding the piston to a size to closely fit an end of the cylinder into which it may be inserted, then introducing such expanded piston into the cylinder and grinding them

together, then a second time permanently heat-expanding the piston and reintroducing it into the cylinder and grinding the two together, and repeating these steps until the cylinder is properly reshaped.

5 5. The process of fitting an engine piston to a cylinder in which it works which consists in first permanently expanding a finished piston to a size to closely fit the bore of the cylinder, and then subjecting it to surface treatment to shape it to the cylinder.

10 6. The herein described process of refitting worn cast iron pistons to cylinders in which they work, which consists in permanently expanding the piston to a size to closely fit an end of the cylinder into which it may be inserted, and then introducing the piston into the cylinder and grinding them together to cause them to accurately fit one

15 20 7. The herein described process of refitting worn cast iron pistons to cylinders in which

they work, which consists in permanently expanding the piston to a size to closely fit an end of the cylinder into which it may be inserted, then introducing the piston into the cylinder and grinding them together, and repeating these steps until the cylinder is reduced to cylindrical form throughout the working stroke of the piston and the latter is expanded to fit the reshaped cylinder.

25 30 8. A new article of manufacture consisting of a cast iron engine piston permanently heat-expanded to working size and having its working surface ground to fit the cylinder in which it is to work.

9. A new article of manufacture consisting of a hollow, cast iron, engine piston permanently heat-expanded to working size and of a specific gravity less than that of ordinary cast iron, and having its working surface operated upon to finish it to fit the cylinder in which it is to work.

WILLIAM A. KNAPP.
